UNITED STATES PATENT OFFICE

2,597,822

SHUTTER FOR INTERNAL-COMBUSTION ENGINES

Joseph Rozen, Wichita, Kans.

Application July 29, 1947, Serial No. 764,364

2 Claims. (Cl. 257—132)

1

My invention relates to an improvement in protective and temperature controlling devices for internal combustion engines of transportation devices.

An object of my invention is to provide an adjustable shield device that may be positioned in front of an internal combustion engine in transportation devices or in front of the radiator of the cooling system of the engine to shield the engine or radiator from snow, rain, extremely cold wind and the like, that would interfere with the proper running or performance of the engine.

Another object of the invention is to provide a device of the kind mentioned, the several shields of which may be operated independently of each other so as to shield the engine or radiator from either side or the top or bottom thereof, or all the shields may be opened as may be desired in fair weather.

A further object of the invention is to provide a device of the kind mentioned in which the shields may be partially opened, to admit the passage of limited amounts of cooling air, whereby the temperature of the engine may be governed to suit the operator of the engine.

A still further object of the invention is to provide a device of the kind mentioned that is simple in construction, inexpensive to make, simple to install, light in weight and is simple and easy to operate. These and other objects will be more fully explained as this description progresses.

Now referring to the accompanying drawings, in which similar numerals of reference designate the same parts throughout the several figures of the drawings.

Fig. 1 is a front view of an airplane to which my invention has been applied.

Fig. 2 is a detail sectional view through an airplane wing and showing a side view of the engine housing to which my invention has been applied, the view being as seen from the line II—II in Fig. 1 and looking in the direction of the arrows.

Fig. 3 is a detail cross sectional view through the engine housing and showing my invention applied thereto, the view being as seen from the line III—III in Fig. 2 and looking in the direction of the arrows.

Fig. 4 is a front view of the device, the engine housing and portions of the shield tracks therein being shown in dotted lines.

Fig. 5 is a plan view of an airplane to which my invention has been applied and showing the operating cables by which the shutters are actuated.

2

Fig. 6 is an enlarged detail sectional view through the engine housing to which my invention has been applied and showing still more clearly the means of actuating the protective shields of the device.

Fig. 7 is a detail perspective view of a portion of the instrument board or other suitable portion of the machine and illustrating the method of adjusting the shields.

Fig. 8 is a section taken on the lines 8—8 of Fig. 4.

In the drawings is shown an airplane fuselage 10 and wings 11 and 12 on which the engine housings 13 and 14 are carried and in which an engine 15 is mounted in the usual manner, the engine 15 having the usual drive or crankshaft 16 that extends forwardly therefrom and through the large circular opening 17 which is concentric with the shaft 16 on which the propeller 18 is rigidly mounted in front of the engine housing 13 or 14 in the usual manner.

My invention consists of a circular frame 19 that is adapted to fit within the engine housing opening 11 and be rigidly attached to the housing 15 by any suitable means such as bolts or welding. The circular frame 19 is provided with a smaller circular element 20 through which the drive shaft 16 of the engine revolvably passes. The small ring 20 is supported on channeled track elements 21 that are rigidly attached thereto and radiate therefrom and are rigidly attached to the large circular frame element 19 to define equally sized portions and shaped portions of the area of the circle defined by the large circular frame 19. At the outer ends of the track elements 21 the track elements divide and extend beyond the large ring 19 and behind the portion of the engine housing to which the large ring 19 is attached to form parallel track elements 21a and 21b, that join onto a still larger ring 19 that fits in the outer circular portion of the housing 13 or 14, as shown in Figs. 3, 4 and 6.

The device is provided with a series of shutter elements b, c, d and e that are made of any suitable material such as plywood, sheet metal, glass, plastic material or the like. If glass or plastic material is used it may be clear or transparent or colored, making it translucent or even opaque.

It is well known that glass of varying colors has an effect on the amount of heat that is readily transmitted therethrough, therefore it may be admissible to use colored glass or plastic material for the shutters b, c, d and e, each of the shutter elements b, c, d and e are carried in a frame 22 that is slidably carried in the parallel track ele-

ments 21a and 21b and which will also fit in the radial channel frame elements 21 when the shutter is in a closed position.

Each shutter is slidably operated by means of a cable 23, one end of which is attached to the outer central portion of the frame 22 and the cable extends outwardly therefrom and thence rearwardly through the interior of the engine housing 13 or 14 and through the wings 11 or 12 and into the fuselage 10 to the instrument panel 24 where it connects to a ratchet toothed element 25 that slidably passes through a slot 26 in the instrument panel 24 and the ratchet teeth of the element 25 will catch on the metal of the instrument panel 24 at the bottom of the slot 26 to hold the shutter b, c, d or e, in radially adjusted positions relative to the circular opening 17 of the engine housing 13 or 14. It will be understood that the cables pass around a system of pulleys such as at 27, 28, 29 and 30 that are located, one at each turn of each cable 23 in its tortuous route from its respective shutter b, c, d and e, to its respective ratchet toothed element 25 at the instrument panel of the machine. Each shutter b, c, d and e is provided with a helical compression spring 31 that is positioned around its respective cable 23 with one end of the spring 31 bearing against the outer member of the shutter frame 22 and the other end of the spring 31 bears against the engine housing 13 or 14. The spring 31 serves to urge movement of its respective shutter and shutter frame toward the center of the circular air opening 17 of the engine housing 13 or 14 as will be readily understood.

The operation of the device is as follows; before starting the engines 15, the engines will be cold or cool and the shutters b, c, d and e will be left in a closed position, thereby denying passage of air through the air opening 17 of the engine housings 13 and 14. As the engine runs it will warm up and when the engine reaches the desired temperature the shutters may be opened to any desired degree by the operator of the machine by pulling outward on the ratchet toothed elements 25 to the desired position where they may be so held by allowing the ratchet teeth of the ratchet toothed element 25 to engage the metal of the instrument panel 24 at the bottom of the slot 26 as shown in Fig. 7. As the plane flies and gains altitude the temperature of the cooling air will change and further adjustments of the shutters b, c, d and e may be made in the same manner as above described to suit the prevailing conditions. As the ratchet elements 25 are released or moved inwardly, the pressure of the springs 31 will move their respective shutter b, c, d or e toward the center of the circular opening 17 to effect a partial or complete closure of the opening 17 as the case may be, thereby limiting or adjusting the amount of cooling air passing by the engine 15 which in turn governs the temperature of the engine.

When an airplane encounters a rain or snow storm, the rain or snow may be traveling from one side or the other of the engine or from the top or even the bottom thereof. In this case, the shutters on one side, top or bottom, may be closed more than those on the opposite side, top or bottom to shield the engine from the rain or snow as will readily be understood.

While the device shown in the drawings and described in the foregoing specification is probably the preferred form of the device, it is to be understood that such modifications of the invention may be employed as lie within the scope of the appended claims without departing from the spirit and intention of the invention.

While the device is shown and described as being applied to an airplane, it is also to be understood that the device is applicable for use on automobiles and devices of various types where internal combustion engines are used. Now having fully shown and described my invention, what I claim is:

1. In a protective and temperature controlling device for internal combustion engines, said engine having a housing therefor and an opening in said housing for the passage of air therethrough for engine cooling purposes, a shutter holder frame, said frame comprising a central frame ring, an intermediate frame ring and an outer frame ring, said central and intermediate frame rings being joined together by radially extending channeled elements that radiate from the central ring to the intermediate ring, pairs of channeled elements, said pairs of channeled elements connecting between the outer ends of the said radially positioned channeled elements and being in a V-shaped position between the said intermediate and outer frame rings, each channeled leg of the V-shape being in parallelism with the next successive channel element of the next successive V-shaped channeled frames, the said intermediate frame ring being positioned around the opening in said housing and the V-shaped channeled elements extending outwardly behind the said housing and from the edge of said opening to the outer ring in the housing, a plurality of V-shaped flat plates, said V-shaped flat plates being slidable radially between the said pairs of parallel channeled elements and being receivable in the radially positioned channeled elements when the V-shaped flat plates are in their closed position, and means for radially moving said V-shaped flat plates independently of one another to and from their closed, partially opened and full open positions.

2. A structure of the character described in claim 1, wherein the V-shaped flat plates are made of light transmitting material and are colored.

JOSEPH ROZEN.
